(57) **CLAIM**

We claim the ornamental design for a safety scalpel cover, as shown and described.

DESCRIPTION

FIG. 1 is a top perspective view of the safety scalpel cover; FIG. 2 is a bottom perspective view thereof; FIG. 3 is a left side elevation view thereof; and, FIG. 4 is a right side elevation view thereof. The broken lines showing environment in the drawings are for illustrative purposes only and form no part of the claimed design.
